UNITED STATES PATENT OFFICE.

JESSE DEAN, OF TRENTON, NEW JERSEY, ASSIGNOR TO MADDOCK & STEEL,
OF NEW YORK, N. Y.

DESIGN FOR A COVERED DISH.

SPECIFICATION forming part of Design No 20,815, dated June 2, 1891.

Application filed October 13, 1890. Serial No. 368,053. Term of patent 7 years.

To all whom it may concern:

Be it known that I, JESSE DEAN, a citizen of the United States, residing at Trenton, in the county of Mercer and State of New Jersey, have invented or produced a new and original Design for Covered Dishes, of which the following is a specification.

The present design consists in the shape of the body and cover of dishes and of the handles for the body and cover.

The accompanying photograph shows a low dish of the character of a soup-tureen or vegetable-dish embodying the design.

Figure 1 is a side view of the dish; Fig. 2, a view looking down on the cover; and Fig. 3 is a view of the bottom of the body of the dish inverted.

The body A of the dish is formed with sloping and rounding sides and ends swelled outwardly at a level about one-third the height of the body and curving thence inwardly as it extends down to the foot a. This foot is flared outwardly, its outline forming a reverse curve, as shown in Fig. 1.

Viewed in plan the dish-body consists of approximately straight sides b b and rounded ends c c, joining one another through the medium of gently-rounded corrugations, as shown in Fig. 3. Midway between the sides and ends the dish-body is formed with slightly-projecting radial ribs d d, as shown in Fig. 3, which ribs, when viewed from the side, conform in shape to the general curve of the sides of the dish, as shown in Fig. 1. On each side of each rib a very slight concave is formed, merging into a convex curve which leads into a depression e, of which there are eight, as shown in Fig. 3. The sides b b and ends c c are formed with convex curves leading into these depressions. The outline thus described is that of the swelled portion of the dish-body, as shown in Fig. 3; but the top or rim of the dish has the same outline only slightly contracted, and the same outline is carried downwardly from the swelled portion toward the foot a, the ribs d and depressions e becoming less distinct as they approach the foot. The same outline is not repeated in the foot, which is formed only with straight sides rounded at

their opposite ends following the outline of the sides b b, as shown at b' in Fig. 3, and with

rounded ends c', joining the sides at indentations e' at four points. The side of the dish-body above its swelled portion is curved slightly inward until close beneath the rim, where it is curved slightly outward, as shown at f f in Fig. 1, so that the rim is made to flare outward to a slight extent.

On each end of the dish-body is a handle B, one end of which is in the form of a leaf g, which is spread out and rests against the end portion of the dish, while its stem springs outwardly from the dish in the form of a loop or arch, the opposite end of which rejoins the dish-body with a slight enlargement or projection h. From this enlargement a leaf i springs, molded in low relief on the surface of the dish and serving as an approximate counterpart to the leaf g, which, however, is in high relief. The middle of the handle is thickened at j with an ornament resembling a leaf turned back and laid against the stem.

The cover C is formed with a convex or dome-shaped top sweeping in a regular curve from the center to the edges or rim. As it approaches the rim the surface is slightly varied to form radial projecting ribs d', corresponding in general position to the ribs d on the dish-body, with the addition of similar ribs k k at the opposite ends of the cover. On opposite sides of these ribs are depressions m m, corresponding in position to the depressions e e on the dish-body. These ribs and depressions are most distinct when close to the rim of the cover and fade away at about one-third the distance from the rim toward the center. The outline of the cover corresponds to that of the dish, having straight sides and curved ends varied by projections at the ribs d' by indentations at the depressions m, and also by slight indentations p p at opposite ends adjacent to the ribs k k.

The cover-handle D is very similar in design to the handles B B, having the same arched stem terminating in a leaf g, spread out upon the cover at one end, and in a projection or enlargement h where it meets the cover at its other end, and from which springs a leaf i in low relief, spreading out upon the cover. The handle is formed on its top with an ornament j in the form of a leaf curved backwardly upon it. It is also ornamented

on its sides by lobe-like corrugations simulating embryo leaves *n*. The cover-handle differs from the dish-handle in that the arched portion simulates two stems meeting at the middle and slightly overlapping, the one terminating in the back-turned leaf *j*, already described, and the other in a downward projection *q*, as shown in Fig. 1.

Those features of my design which I believe to be characteristic ones distinguishing it from prior designs are the shape of the dish-body, with especial reference to the peculiar-shaped corrugations near the ends, near and between the ribs *d* and grooves *e e*, the merging of these corrugations into the foot, having curved ends *c'* and indentations *e'*, the end handles *B B*, the shape of the cover with its peculiarly curved scalloped outline and its ridges *k* and *d'*, and the cover-handle *D*.

What I claim is—

1. The design for a covered dish, substantially as shown in the accompanying photograph.
2. The design for the end handles of a dish, substantially as shown in the accompanying photograph.
3. The design for the cover-handle of a dish, substantially as shown in the accompanying photograph.

In witness whereof I have hereunto signed my name in the presence of two subscribing witnesses.

JESSE DEAN.

Witnesses:

PETER W. CROZER,
WILLIAM S. MILLS.
